ARTHUR J. MANKIN, OF PHILADELPHIA, PENNSYLVANIA, ASSIGNOR TO TRIUMPH
HOSIERY MILLS, INC., OF NEW YORK, N. Y., A CORPORATION OF NEW YORK.

KNITTING MACHINE.

Application filed June 30, 1926. Serial No. 119,693.

The invention relates to knitting machines and relates more particularly to the rotary or circular type of knitting machines, such as is exemplified in spring needle machines 5 of the Wildman type. The invention contemplates as its general object to provide means adapted to be used in connection with a knitting machine of the character described, for automatically forming a reinforcing splice on the work in the desired 10 locality and while the same is being knitted. More particularly, the invention is designed to provide means for forming a reinforced splice portion of stepped configuration on 15 ladies' hose.

The present application is a continuation in part of my prior application Serial No. 23,491, filed April 16, 1925, allowed January 6, 1926, and bearing No. 1,594,421. While 20 the present invention is directed to certain improvements and advantages not present in my allowed application, the basic principles involved are the same and have been enlarged upon in detail in said allowed application. Therefore reference to said allowed 25 application will lend itself to a more clear understanding of the present improvements.

Briefly stated my allowed application above referred to concerns the provision of 30 a ring attachment designed to be applied to and used in connection with spring needle knitting machines of the character described and having automatic cam mechanism co-operating therewith to selectively and progressively control and actuate predetermined 35 blocks of needles in the cylinder which results in a high splice design of stepped configuration and of colored thread if desired being knitted as an additional thickness in 40 the heel portion of ladies' hose. The ring member surrounds a needle cylinder and carries needle butt members or blocks which in turn are actuated and controlled by movable and stationary cam elements which are 45 automatically drawn into operation at the desired time in the progress of knitting the stocking.

The present improvements, while broadly including the mechanism for accomplishing 50 the objects described, are directed to certain improvements in the ring member and the needle controlling elements carried thereby for automatically and progressively throwing into operation successive blocks of 55 needles for forming the stepped high splice

in the heel portion of the stocking. In my aforesaid allowed application the widest portion of the splice is at the lower part of the heel and thereafter the sole and toe portion of the stocking are completed in the usual manner incident to machines of this type and irrespective of the presence of the ring member and its associated elements. The present improvements further contemplate in this regard means for automatically 65 knitting a reinforcing splice of stepped configuration and of different colored yarn in the sole portion of the stocking after a similar stepped splice has been knitted as described into the heel portion. The reinforced stepped splice provided by the present improvements is commenced after the heel portion has been knitted and at the time the yarn needles for knitting the sole portion are drawn into operation. By the present 70 improvements different colored yarns are utilized for knitting the heel and toe portions of the stocking. The needles for forming the stepped reinforcing splice in the sole of the stocking are the same which are utilized for forming certain of the steps in the configuration of the heel splice, and the elements of the ring member controlling these needles are the same in each instance. Means are provided in the present improvements 75 for cooperating with the ring member to knit the stepped splice in the sole portion at the proper interval after the stepped splice in the heel has been completed.

With such objects in view as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration.

In the said drawings:

Fig. 1 is a perspective view of a portion of a spring needle knitting machine of the

character described and illustrating only such parts as are necessary to a complete understanding of the present improvements.

Fig. 2 is a similar view looking from the opposite side of the machine and illustrating more clearly the ring element shown in Fig. 1 and also showing the automatic cam mechanism for actuating the needle controlling elements carried by said ring member.

10 The mechanism for feeding thread to the needles for the various and successive steps in the knitting of the stocking and shown in Fig. 1 has been omitted in this figure.

Fig. 27 is a detail fragmentary perspective view of the yarn finger 4 illustrated in Fig. 1 and looking from the opposite side of the 95 finger as viewed in the latter figure.

Referring to the drawings, and with particular reference to Figs. 1 and 2, the knitting machine in conjunction with which the attachment is designed to be used comprises 100 the usual vertical standards 1 and top portion 2. The knitting cylinder or head is indicated at 3 and is adapted to be rotated from the power source of the machine in the usual manner. The rotating needle head 105 3 carrying the vertical needles 3^a is designed to contact and cooperate with the usual stationary cams (not shown) by means of which the needles are automatically and periodically raised and lowered to catch and clear 110 the thread or yarn and perform the knitting operation in accordance with the usual known practice in machines of this character.

Referring to Fig. 1, the main yarn guides 115 or fingers are shown at the left hand of the machine and this mechanism constitutes a preferred or known construction in machines of this type. It will be sufficient to state that the main yarn fingers 4, 10, 5, 6, 7 and 8 are raised or lowered by corresponding cams 9 through the medium of interposed cooperating levers indicated at 14 when it is desired to place the yarn fingers out or in knitting position. The main yarn or thread 125 strands are indicated at 15 and are fed from suitable spools or rolls (not shown) to the outer ends of the yarn fingers 4, 10 and 5 to 8. It will be understood that when the yarn fingers are raised the needles 3^a are un- 130

able to catch the yarn while the needles are rotating.

The high splicer finger is indicated at 16 and is designed to be raised or lowered by 5 the cam 17 through the action of lever 18 when it is desired to place the splicing yarn out or in knitting position. The high splice thread or yarn 19, which may be of varicolored thread if desired, is conducted from 10 the usual roll (not shown) through an upright tubular guide post 20 and to the end of the high splicer finger 16 where it is engaged or cleared by certain of the needles 3^a according to whether the high splicer finger 15 is in or out of knitting position as determined by the cam 17 and lever 18. The main 20 yarn finger cams 9 and the high splice finger cam 17 are caused to rotate by the usual ratchet and pawl mechanism, acting by power through the rocking movement of a 25 suitable lever loosely mounted on a transverse shaft and rocked by power applied through the movement of such lever. Such mechanism is shown in my allowed application above referred to and the described lever is automatically and periodically reciprocated from the power source of the machine to move the yarns carried by the main 30 yarn fingers 4 to 8 and high splicer finger 16 into and out of position to be engaged and caught by the rotating needles 3^a of the needle cylinder 3, as determined by the progress of the work.

It will be understood that the procedure 35 described is common practice in knitting machines of this character. The means for knitting the stepped high splice at the heel portion of the stocking are shown and described in my allowed parent application 40 referred to and broadly stated comprise a ring member having vertically reciprocable blocks for controlling the short needle butts and successively actuating the same at the proper interval when the heel is reached. 45 Similar means are provided in the present application for knitting this stepped high splice at the heel portion, but the same include certain structural improvements and modifications not present in my said allowed 50 application.

In the present instance the ring member as shown at 40 is preferably constructed of metal and consists of two semi-circular sections 40^a and 40^b adapted to be removably 55 attached to the needle cylinder of the machine (Figs. 3 and 4). The assembled ring member 40 is adapted to be removably secured as by screws 41 passing through apertures 42, to the rotating cylinder dial 44 of 60 the knitting machine (Fig. 5). One of the ring sections 40^b is formed with a plurality of spaced vertical grooves 45 having intervening ribs or guides 46 preferably cast integrally with the ring section. A plurality 65 of housing members 47, also preferably of

metal and having cut away recessed portions 48 on their inner sides are designed to be removably secured to the ring member 40 by means of screws or fastening means 49 passing through suitable apertures 49^a in the 70 housing members, said screws having a threaded engagement at their inner ends with suitable spaced apertures 49^b in the ribs or guide members 46 of the ring section 40^b. Each housing member 47 is further provided 75 with cut away portions 49^c in their side walls and a recessed horizontal groove 49^d in its rear wall, said cut away portions being preferably disposed between the screw apertures 49^a of the housing member and the purpose 80 of which will be described.

A plurality of block members 50, each having a pair of vertically extending spaced lugs 51 are designed to be housed within the members 47 with the upstanding portions 51 arranged on each side of the ribs or guides 46 of the ring section. The block members are designed to have a free vertical sliding movement within the housing members 47 when the device is assembled. 90 Transverse recessed portions 52 are provided in the upstanding portions 51 of the block members (Fig. 2) and spaced in such manner that when assembled said recessed portions 52 are opposite the corresponding 95 transverse recess 49^d in each of the housing members 47. A coil spring or band 43 of circular configuration (Fig. 14) is designed to encircle the sections 40^a and 40^b of the assembled ring element, suitable peripheral 100 grooves 48^a being provided in the ring sections, Figs. 6 and 7, to receive the spring when the ends of the latter are hooked together. The construction described results in spring member 43 being contained within 105 the notches 49^c and groove 49^d in the housing members 47 when the latter are secured to the ring section 40^b and the spring member engages the transverse recessed portions 52 of the vertically reciprocable block members 50 110 to removably maintain the latter in their normal upper position (Figs. 5 and 8).

The lower ends of the blocks 50 are provided with outwardly projecting lugs 53 which as best seen in Fig. 3 are of varying 115 lengths. The blocks 50 are equally spaced on each side of the vertical center of the ring section 40^b as viewed in Fig. 3, and the innermost pair of blocks 50, one on each side of the center, are provided with the 120 shortest outwardly projecting lugs 53. Thence the succeeding pairs of lugs increase successively in length as at 53^a, 53^b, 53^c, 53^d and 53^e, the outermost lugs 53^e being of greatest 125 length. The lower ends 50^e of the vertically reciprocable block members 50 are designed to engage the butt jacks 62 of the short butt needles carried by the needle cylinder 3 when the blocks are moved downwardly, as shown in dotted lines in Fig. 8, and when the device 130

is in operation to knit the heel splice of the stocking. The projecting lugs 53 to 53^e are engaged by movable and stationary cam members carried on the machine adjacent to the needle cylinder in a manner clearly described in my allowed application herein referred to. It will be sufficient to state that the variation of length of the lugs 53 to 53^e results in progressive actuation of the short butt needles 62 to successively knit from the narrowest to the widest portion of the stepped splice in the heel, shown at A in Fig. 20, and the lugs 53 to 53^e are engaged and knocked downwardly to control the short butt needles as the ring 40 rotates with the cylinder past the cam members referred to and located adjacent said cylinder in the path of the lugs.

The mechanism for controlling the short needle butts to successively knit the steps in the heel splice and which is enlarged upon in detail in my parent application will be briefly described herein. This mechanism is illustrated in Figs. 15 and 18 and in the upper portion of Fig. 2. Referring to these figures, a block or support 54 is suitably secured to and rigidly mounted on the top portion or table 2 of the machine. The support has removably secured thereto a stationary cam member 56 which projects directly under the rotating ring 40 in such manner as to engage the lugs 53 to 53^e and move the same and their blocks 50 to their normal upper position against the ring when the latter is revolved, where the blocks are yieldably maintained by the circular coil spring or band 43 as described. The support 54 is further provided with a curved stationary cam member 57 (Fig. 18) so positioned as to project into the path of the long needle butts 58 of the usual needles 3^a which latter are thereby deflected downwardly and temporarily out of operating position until they have passed the various cams carried by the support 54. This action is to temporarily separate the long butt needles 58 from the short butt needles 62 and permit the subsequent progressive selection and actuation to knit the stepped splice. The short butt needles for effecting the design, as best seen in Fig. 18, are not engaged by the cam 57 to be moved downwardly but pass freely by this cam. These short butt needles are designed to be moved upwardly by a horizontally reciprocating cam member 59 suitably secured as by a pin and slot connection for horizontal movement relative to the block 54. It will be understood that when the cam member 59 is in its innermost position as shown in Fig. 18, the short needle butts 62 will be engaged by the said cam and moved upwardly due to the wedge-shaped configuration of the engaging portion of the cam member. This upward movement of the short butt needles places them in

position on the cylinder to be subsequently engaged by the blocks 50 when the latter are selectively moved downwardly as described above. The blocks are normally maintained in their uppermost position during the operation of the machine by means of the stationary cam 56 which engages all of the lugs 53 to 53^e of said blocks as the ring rotates. For progressively controlling the blocks 50 a cam member 74 is mounted for horizontal movement relative to the ring and cylinder by means of screws passing through a suitable slot in the cam member. When the cam 74 is in its innermost position all of the lugs 53 to 53^e are engaged thereby and move downwardly to be thereafter engaged and lifted by the cam 56. As the cam 74 is periodically and progressively moved outwardly by the cam mechanism shown in Fig. 15, the lugs 53 having the shortest length are first cleared by the cam 74 with the result that the short butt needles lifted to operative position by cam 59 are permitted to remain in position and the first or narrowest step of the splice is knitted. On the next outward movement of the cam 74 the next shortest pair of lugs 53^a are cleared by this cam with a result that short butt needles controlled by blocks 53 and 53^e remain in operation with the result that the second or next widest step of the design is knitted. This step-by-step outward movement away from the needle cylinder of cam 74 is controlled by cam wheel 86 which is periodically rotated with a step-by-step movement from the power source of the machine, and is clearly described in my allowed application above referred to. It will be sufficient to state that the cam 74 is progressively moved outwardly by means of steps 86^a on the periphery of the cam wheel 86 which are successively engaged by roller 84 on lever 82 pivotally connected at its free end to the vertical rod 80 having at its upper end a cam face 77 engaging a recess 79 in the cam 74. The latter is normally forced inwardly to engage all of the lugs 53 to 53^e by means of a spring 96 engaging said cam and secured at its lower end to the frame 2 of the machine. Referring still to Fig. 15 during the normal knitting of a stocking the roller 84 engages the smooth periphery of the wheel 86 with a result that cam 74 is held in its outermost position to clear all the lugs 53 to 53^e, by means of the cam face 77 engaging slot 79 in cam 74. At this time the lower cam end 70 of rod 68 depends in its lowermost position at one side and free of cam wheel 86, said cam 70 and rod 68 being held downwardly by the pressure of spring 90 engaging and disposed between the lower end of said rod and a bracket 69 on the machine. In this position it will be apparent that cam 59 is in its outermost position to clear the short needle butts with the result

that the latter are not moved to operating position and the normal knitting of the stocking is performed by the usual long butt needles controlled by the usual cams (not shown) of the machine. At a predetermined time when the heel portion of the stocking is reached and the design is to be knitted, the highest tooth or step 86^a engages roller 84 and cam 74 is thereby moved from its outermost to its innermost position to engage all of the lugs 53 to 53^c of the block members 50 to thereby move the same downwardly, releasing them from their yieldable retaining spring 48. At the same moment that this action occurs projection 71 on the opposite side of cam wheel 86 engages cam 70 moving the same upwardly against the pressure of spring 90 and projecting cam 59 into the path of the short butt needles 62 to move the same upwardly into operating position and within the control path of the blocks 50. The projection 71 is of such length as to engage cam 70 and maintain cam 59 inwardly as long as roller 84 is in engagement with the successive steps 85^a of cam 86. As the roller 84 progressively engages each step 86^a, and dwelling for a short time at each step, it will be apparent that cam 74 is progressively moved outwardly to successively and respectively clear lugs 53 to 53^c, and this results in the stepped splice being knitted at the heel portion of the stocking. When the latter is completed cam 70 clears projection 71 and is forced downwardly by spring 90 resulting in cam 59 being moved out of the path of the short needle butts and the knitting of the stocking proceeds by the long needles in the usual manner.

I will now describe the mechanism for knitting into the heel of the stocking a different colored yarn from that used in knitting the toe. As best seen in Fig. 1, the yarn fingers 4, 5, 6, 7 and 8 are individually actuated by their respective cams 9 at predetermined intervals in the formation of a stocking, and each yarn finger performs one or more operations toward the completion of the article. The manner and interval of operation of these yarn fingers 4 to 8 has been fully described in my allowed application in which said yarn fingers are illustrated and described. In the present invention and for the purpose of knitting a different colored yarn in the heel from that used in knitting the toe, an additional finger 10 is added as illustrated in Fig. 1. Yarn finger 4 is utilized in knitting the heel and toe of the stocking and for this reason this yarn finger is utilized to control additional yarn finger 10 and moves the latter into knitting position when it is desired to include the different colored yarn into the heel and toe portions.

An upright member or post 100 is provided on the top 2 of the machine and is

standard equipment in machines of the type with which the present improvements are designed to be used. A frame member 101 is secured to the top of the upright 100 and projects forwardly toward the knitting cylinder. The member 101 supports at its outer end the take-up wires 102 and 103 respectively for yarn fingers 10 and 4. A bifurcated clamp member 104 having a downwardly extending control rod 105 normally rests on the yarn strands 15^a and 15^b, and by clamping the latter against the frame prevents the yarns from moving during the ordinary process of knitting a stocking. The lower end of the control rod 105 is pivoted at 106 to one end of a rocking lever 107 in turn pivoted as at 108 to the machine frame, and rocking lever 107 is designed to be engaged at the proper interval by a projection or lug 109 of a cam wheel 110 suitably actuated and rotated from the power source of the machine. The elements immediately described are standard equipment of spring needle type knitting machines.

A rocker arm 111 is pivoted at 112 to the upper end of an ear 113 and the lower end of said ear is secured by suitable means 114 to the forwardly extending frame member 101. One end of the pivoted rocker arm 111 has secured thereto a depending clamping member 115 adapted to engage when desired and hold against movement take-up wire 103 controlling the operation of yarn finger 4. The opposite end of the rocker arm 111 has secured thereto a depending lever 116 provided at its lower end with a manually operable jaw clamp 117 normally urged to closed position by a spring member 118. The jaw clamp 117 is designed to preferably engage and clamp a headed pin or stud 119 projecting laterally from one side of the yarn finger 4. The depending lever 116 has secured thereto as at 120 a clamping member or rod 121 (Fig. 25). The latter extends rearwardly and at its free end is adapted to engage and clamp when desired the take-up wire 102 controlling colored yarn finger 10, thereby preventing when desired the knitting operation of this finger. Yarn to the yarn finger 4 for the heel and toe of the stocking is shown at 15^a and is supplied from a suitable reel (not shown) to yarn finger 4 (Fig. 1). The colored yarn for yarn finger 10 is shown at 15^b and is supplied from a similar reel (not shown) to the end of yarn finger 10.

The operation of the devices described for controlling the knitting of colored yarn into the heel and toe of the stocking is as follows: The stepped splice in the heel of the stocking and illustrated at 30 to 35 in Fig. 20 has been knitted by means of the ring member 40 and its associated cam elements and needle controlling blocks 50 as heretofore described. When the knitting has proceeded to the

point 37 in Fig. 20 it becomes desirable and necessary to throw yarn finger 4 into operation to knit the heel of the stocking. In the ordinary operation of the machine and in the absence of the present improvements this would be accomplished in due course by projection 109 on cam wheel 110 striking the rocking lever 107, thereby raising control arm 105 and releasing clamp 104 from take-up wire 103 controlling the feeding of yarn to finger 4. The latter has been lowered at this time to knitting position by its individual cam 9 controlled from the power source of the machine in the usual manner. In the present improvements when the yarn finger 4 is dropped in knitting position lever 116 is pulled downwardly, rocking arm 111 on its pivot and releasing clamp 115 from take-up wire 103, thereby permitting the feeding of yarn to finger 4. Simultaneously this downward movement of lever 116 engages clamp 121 with take-up wire 102 thereby preventing the feeding of yarn to finger 10. When it is desired to knit colored yarn into the heel portion of the stocking and when yarn finger 4 is elevated by its cam 9 out of knitting position, this movement elevates lever 116 to rock arm 111 and clamp 115 engages take-up wire 103 thereby preventing further feeding of yarn to finger 4. This movement releases clamp 121 from take-up wire 102 and colored yarn 15^b is free to be fed to yarn finger 10 to be knit into the sole of the stocking. After the sole of the stocking has been completely knit up to the point 39 (Fig. 20) the different colored yarn is designed to be knit into the toe. Cam 9 under finger 10 permits said finger to be lowered to knitting position and yarn 15^b is fed through take-up wire 102 to finger 10 to be knit into the toe of the stocking.

The mechanism for knitting a reinforcing portion of stepped configuration of plain or colored yarn in the sole portion of the stocking, and illustrated at 34^a and 35^a in Fig. 20, will now be described. The same block members 53^c and 53^d which are employed to control the short needle butts in producing the two lowermost or widest steps 34, 35 in the heel splice, are further utilized in forming the steps 34^a and 35^a in the sole portion. Referring now to Figs. 1, 2, and 20 to 23, and especially to Fig. 2, a modified structure of the machine is illustrated for performing this operation in the sole of the stocking.

At the finish of the heel knitting operation the machine proceeds to knit the sole in double thickness, yarn finger 8 being in and high splice finger 16 being in, forming a double or reinforced sole. At a predetermined period during the knitting of the sole it is desired to knit the splice portion illustrated at 34^a and 35^a in Fig. 20. The cam wheel 86 is provided as illustrated with

two stepped projections 125 and 126. At this stage of operation the cam wheel 86 is rotated until projection 125 is in lowermost position and ready to be engaged by roller 84 of lever 82, the cam 86 is revolved in a counter-clockwise direction approximately 180° from the position illustrated in Fig. 2. At this time cam face 77 of rod 80 is in its down position thereby holding movable cam 74 out of the path of the lugs 53, 53^c and 53^d against the pressure of spring 96. When roller 84 rides up on projection 125 cam head 77 is elevated and spring 96 forces cam 74 inwardly into the path of lugs 53^c, 53^d of the block members 50 carried by the ring 40. This results in reinforced step 34^a (Fig. 20) being knitted as illustrated in the sole portion of the stocking by the short needle butts controlled by lugs 53^c. It will be understood from an earlier description that the short needle butts 62 are only moved into the control zone of lugs 53^c when cam 59 is in its inward position. Therefore simultaneously with the engagement of projection 125 with roller 84 to move cam 74 into the path of lugs 53^c, 53^d, a projection 127 on a wheel 128 on the power shaft 73 of the machine contacts with the end 129 of a rocker arm 130 pivoted on a stud shaft 131 secured to the machine frame. An extension 132 of the rocker arm 130 has secured thereto as by screws 133 a second arm member 134. The lower end of arm 134 is adjustably secured by means of threaded nuts 135^a engaging ear 136^a, to the lower end of the link or rod 68. The outward rocking movement of arm 130 caused by contact of projection 127 with said arm results in rod 68 being moved downwardly and cam 59 is moved inwardly by a bell crank 63 into the path of the short needle butts. The latter are elevated by cam 59 into the zone of control of the lugs 53^c for the first step 34^a of the design of the sole, and by lugs 53^d, 53^d for the second step 35^a of the sole.

After the first step of the design is knitted by lugs 53^c projection 126 engages roller 84 thereby elevating cam face 77 of rod 80 and permitting cam 74 to be forced inwardly by spring 96 a distance sufficient to engage lugs 53^d, 53^d with the result that the second step 35^a of the sole design is knitted.

It is essential that cam 59 be securely held in its inward position while the steps 34^a and 35^a in the sole are being knitted. To this end locking devices are provided to insure this result. The outward swinging movement of rocker arm 130 (Fig. 2) swings outwardly and downwardly arm 134 and a pin or projection 135 on arm 132 engages a latched recess 136 in a curved arm 137 pivoted at 138 to a bracket 139 rigidly secured to the machine frame and said arm 137 is normally pressed inwardly by a leaf spring 140 secured at its lower end as at 141

to the frame of the machine. It will be apparent that the engagement of projection 135 with notch 136 locks arms 132 and 134, rod 68, bell crank 63 and cam 59 in innermost 5 position after the engagement of projection 127 on wheel 128 with the outer end 129 of rocker arm 130 to move the latter outwardly.

Means are provided to release cam 59 from its innermost position at the conclusion of 10 the knitting of the stepped sole configuration, at which time it is desired to remove cam 59 from the path of the short needle butts. At precisely the time that projection 126 passes out of contact with roller 84 at 15 the conclusion of the knitting through the instrumentality of lugs 53^a, 53^b, a projection or lug 142 on a wheel 143 on the power shaft 73 of the machine strikes the upper end of a curved lever or rocker arm 144 loosely and 20 pivotally mounted on stud shaft 131. An adjustable stud 145 is secured as by threaded stem 146 and lock nut 147 to the rocker arm 144 (Fig. 23). Rocker arm 144 is normally urged inwardly into the path of projection 25 142 on wheel 143 by means of a pin or projection 148 on the upper end of the curved arm 137, the latter as above stated being normally forced inwardly by leaf spring 140. The outward movement of rocker arm 30 144 when engaged by projection 142 results in the curved arm 137 being rocked outwardly on its pivot 138 and against the pressure of spring 140 to release projection 35 135 of arm 132 from engagement with notch 136 in curved arm 137. On the release of this locking engagement retractile spring 149 secured at one end as at 150 to the machine frame and engaging at its other and extension 132 of rocker arm 130, rocks 40 the latter on the stud shaft 131 thereby elevating rod 68 and moving cam 59 to its outer position out of the path of the short needle butts. This movement takes place at one quarter of a revolution before the 45 operation of knitting the toe of the stocking which is carried out in the usual manner and through the instrumentalities above described and further enlarged upon in my allowed application herein referred to.

50 What I claim is:

1. An attachment for spring needle knitting machines comprising a ring member carried by the needle cylinder, reciprocable lugs carried by said ring member for controlling the short butt needles of said cylinder, a cam member adapted to be projected into the path of said short butt needles to move the same into the control zone of said ring member, means for automatically actuating said cam member, cam mechanism for automatically controlling the actuation of said reciprocable lugs, and a spring controlled latch for locking said projecting means in the path of said short butt needles during their period of control by

said needle control means carried by said ring member.

2. An attachment for spring needle knitting machines comprising a ring member carried by the needle cylinder, means carried by said ring member for controlling the short butt needles of said cylinder, means adapted to be projected into the path of said short butt needles to move the same into the control zone of said ring member, 70 means for automatically actuating said projecting means, means for automatically controlling the actuation of the short butt needle controlling means carried by said ring member, and means for locking said 75 projecting means in the path of said short butt needles during their period of control by said needle control means carried by said ring member.

3. An attachment for spring needle knitting machines comprising a plurality of ring sections adapted to be detachably secured to surround the needle cylinder of the machine, a plurality of needle engaging block members carried by one of said sections and reciprocable relative thereto, a plurality of housing members removably secured to said ring section to house said block members, and spring means removably secured to said ring sections and engaging said block members to yieldably maintain the same against movement relative to said ring section. 85 90

4. An attachment for spring needle knitting machines comprising a pair of ring sections adapted to be secured together, to 100 surround the needle cylinder of the machine, one of said sections having a plurality of spaced guide ribs, a plurality of needle engaging block members carried by one of said sections and reciprocable relative thereto, a plurality of housing members removably secured to said ring section to house said block members, and a coil spring surrounding the assembled ring sections and engaging said block members within said housing 105 members to yieldably maintain said block members against movement and in alignment within said housing members. 110

5. An attachment for spring needle knitting machines comprising a pair of ring sections adapted to be secured together to surround the needle cylinder of the machine, one of said sections having a plurality of spaced guide ribs, a plurality of needle engaging block members carried by one of said sections and reciprocable relative thereto, a plurality of housing members removably secured to said ring section to house said block members, and a coil spring surrounding the assembled ring sections and engaging said block members within said housing members to yieldably maintain said block members against movement and in alignment within said housing members, and means carried by said block members 115 120 125 130

adapted to be engaged by cam mechanism to reciprocate said block members relative to said ring sections, whereby predetermined needles of said needle cylinder are engaged by said block members and a reinforcing splice is knitted by other than said predetermined needles engaged by said block members.

6. In a spring needle knitting machine, 10 in combination with a rotating needle cylinder and main yarn fingers: splicing needles having short butts carried by the needle cylinder, a ring member carried by the needle cylinder, means carried by said ring member for controlling said short butt needles of the cylinder, means adapted to be projected into the path of said short butt needles to lift the same into the control zone of said ring member, means for automatically actuating said projecting means, means for automatically controlling the actuation of said short butt needle controlling means carried by said ring member, means for locking said projecting means in the path of said short butt needles during their period of control by said needle control means of said ring member, and means for releasing said projecting means after the period of short butt needle control by said needle control means.

7. In a spring needle knitting machine, the combination of a rotatable needle cylinder, short butt needles and long butt needles carried by said cylinder, means for moving 35 to inoperative position said long butt needles, means for elevating said short butt needles to operative position, progressively movable means controlling said short butt needles to successively clear predetermined elevated units of the same, means operative from the power source of the machine for controlling the movement of said progressively movable means, and locking means for holding said elevating means in the path of said short butt needles during the interval the latter are controlled by said progressively movable means, whereby said units will knit a splice design having successive steps of increasing widths in the heel portion of a stocking.

50 8. In a spring needle knitting machine, the combination of a rotatable needle cylin-

der, short butt needles and long butt needles carried by said cylinder, means for moving to inoperative position said long butt needles, means for elevating said short butt needles to operative position, a progressively and outwardly movable cam member controlling said short butt needles to successively clear predetermined elevated units of the same, a cam member operative from the power source of the machine and progressively rotatable with a stop motion to control the outward movement of said progressively movable cam member, and locking means for holding said elevating means in the path of said short butt needles during the interval the latter are controlled by said progressively and outwardly movable cam member whereby said needle units will knit a splice design having successive steps of increasing widths in the heel portion of a stocking.

9. In a spring needle knitting machine, the combination of a rotatable needle cylinder, short butt needles and long butt needles carried by said cylinder, means for moving to inoperative position said long butt needles, means for elevating said short butt needles to operative position, a progressively and outwardly movable cam member controlling said short butt needles to successively clear predetermined elevated units of the same, a rotary stepped cam member operative from the power source of the machine and progressively rotatable with a stop motion to control the outward movement of said progressively movable cam member, whereby said needle units will knit a splice design having successive steps of increasing widths in the heel portion of a stocking, connecting devices between said rotary cam member and said outwardly movable cam member, the respective movements of both of said cam members being in timed relation to the knitting operation of said elevated needle units and locking means for holding said elevating means in the path of said short butt needles during the interval the latter are controlled by said progressively and outwardly movable cam member.

In testimony whereof I affix my signature.

ARTHUR J. MANKIN.
